UNITED STATES PATENT OFFICE.

JAMES M. GREEN AND CARL J. KJENSTAD, OF HAYTI, SOUTH DAKOTA.

MOTOR-DRIVEN SNOWPLOW.

Application filed May 23, 1927. Serial No. 193,556.

This invention relates to a motor driven snow plow, and has for its object to provide, in a manner as hereinafter set forth a plow of such class for expeditiously removing 5 snow and further whereby the snow when removed can be selectively discharged at either side of the line of travel of the plow.

A further object of the invention is to provide, in a manner as hereinafter set forth a 10 plow of such class including snow cutting means operating synchronously with snow removing or delivering means of the suction type, and acting on the snow in advance of the removing or delivery means whereby the 15 latter is relieved from strain during the operation thereof and the snow removing or delivering operation greatly facilitated.

A further object of the invention is to provide, in a manner as hereinafter set forth a 20 motor driven snow plow including snow cutting means and snow removing or delivery means operating synchronously with the snow cutting means, and further providing the plow with means whereby the cutting and 25 removing or delivery means can act upon the snow at different levels.

Further objects of the invention are to provide, in a manner as hereinafter set forth a motor driven snow plow which is comparatively 30 simple in its construction and arrangement, strong, durable, compact, adjustable, thoroughly efficient in its use, capable of delivering snow either to the right or left of the line of travel thereof, readily assembled, 35 and comparatively inexpensive to set up.

With the foregoing and other objects in view the invention consists of the novel construction, combination and arrangement of parts, as hereinafter more specifically 40 described, and illustrated in the accompanying drawings wherein is shown an embodiment of the invention, but it is to be understood that changes, variations and modifications can be resorted to which fall within the scope of the 45 claims hereunto appended.

In the drawings wherein like reference characters denote corresponding parts throughout the several views:—

Figure 1 is a top plan view of a motor 50 driven snow plow in accordance with this invention.

Figure 2 is a side elevation thereof.

Figure 3 is a fragmentary view in longitudinal section.

Figure 4 is a front elevation broken away.

Figure 5 is a section on line 5—5 Figure 1.

Referring to the drawings in detail, a motor driven snow plow in accordance with this invention comprises a chassis consisting of a front bar 1, a pair of side bars 2, 3, and end 60 bar 4, transverse brace bars 5, 6, spaced longitudinally extending supporting members 8, 9, 10 and 11, which are arranged between the brace bars 5 and 6, and longitudinally extending supporting members 12, 13, 65 arranged between the rear bar 4 and transverse brace bar 5. The bars and supports which constitute the chassis are secured together by holdfast devices 14. The front bar 1 is of greater length than the rear bar 4. 70 The side bars 2, 3 incline in opposite directions with respect to each other and the inclination is outwardly from the rear end to the forward end of the side bars 2, 3. The front bar 1 is secured to the side bars, rearwardly with respect to the forward ends of 75 said side bars and the portions of the side bars 2, 3 which project forwardly from the front bar 1, are indicated at 15. The bars 1, 4, 5 and 6 of the chassis are in the form of I-bars and the side bars 2, 3 are in the form of channel bars.

The bar 1 has secured to its upper face a pair of spaced bearings 16, 17. The bar 6 has secured to its upper face a pair of spaced 80 bearings 18, 19 aligning respectively with the bearings 16, 17. Secured to the supporting members 8, 9 is an internal combustion motor 20 for driving the shaft 21 which is journaled in the bearings 16, 18 and projects forwardly with respect to the front bar 1 of the chassis. Secured to the supporting member 10, 11 is an internal combustion motor 22 for driving a shaft 23, which is journaled in the bearings 17, 19 and extends forwardly from 90 the front bar 1 of the chassis. Secured to the spaced supports 23' which extend from bar 6 to the inverted yoke shaped member 55, is an internal combustion motor 23" for propelling the plow. The motor 23 operates a rearwardly directed drive shaft 24, which drives a differential 25, for driving the rear wheels 27 carried by the rear axle 26. Brace members 28 extend forwardly from the rear wheels 27, and are connected with the transverse brace bar 6. Connected to the supports 12, 13 is a transverse suspension member 26' which is connected to the rear spring 26" and the latter is connected at its ends with the axle.

The plow includes a front truck which is pivotally connected with the transverse bar

6 of the chassis. With reference to Figures 3 and 5 the front truck comprises an axle 29 having a pair of pivoted spindles 30 for the front wheels 31 of the plow. The spindles are 5 connected to pivot bolts 32 mounted in knuckles 33. The bolts are provided with crank arms 34, connected together by a rod 35, which forms a part of a steering mechanism 36, having a steering wheel 37 arranged 10 rearwardly of the member 55. The steering mechanism is of known construction. Mounted against the top and bottom of each knuckle 33 are respectively coupling members 38, 39 and through which the pivot bolts 32 extend. The coupling members 38, 39 have 15 their rear ends suspending below and pivotally connected with the bar 6, as at 40, by hanger pieces 41 and bolts 42. The rear ends of the coupling members are torsionally 20 twisted, see Figure 3. Connected to the ends of the bar 6 are forwardly extending, oppositely disposed and inwardly inclined brace members 43, which are loosely connected to the axle 29, as at 44. See Figures 3 25 and 5. The coupling members pivotally connect the front truck to the chassis.

For the purpose of elevating and lowering the forward end of the chassis, a pair of elevating screws are provided and which are indicated at 54, see Figure 5. The elevating screws 54 are provided with hand wheels 54' at their upper ends. Said screws 54 have threaded engagement, as at 54'', with an inverted yoke shape member 55, which extends 30 transversely with respect to the chassis and has its arms 56, fixedly secured as at 57 to the side bars of the chassis. The yoke 55 extends a substantial distance above the chassis and the screws 54 bear against and engage 35 in socket forming members 55' secured upon the top of the axle 29 of the front truck. By adjusting the screws 54 the front of the chassis can be elevated and lowered relative to the front truck due to the front truck being pivotally connected to the chassis.

Arranged forwardly of the chassis, as well as extending above and depending below the same is a housing 58 provided with a pair of spaced fan chambers 59, 60 and in which operate respectively suction fans 61, 62. The housing 58 is formed with an open front and the fan chambers are arranged at the rear thereof. The intake for each chamber is indicated at 63. The side bars 2, 3 extend into 55 the housing 58 and secured to the sides thereof. The forwardly projecting portions of the side bars 2, 3 of the chassis, and which are indicated at 15, see Figure 1 are fixedly secured to the housing for the purpose of suspending the latter forwardly of the chassis. The shafts 21, 23 extend into the housing, and carry cutters 64, 65 respectively which are arranged within the housing at the open front thereof and in advance and spaced from the fans 61, 62 respectively. The cutters op-

erate forwardly of the intakes 63 for the fan chambers.

Leading from the fan chamber 59 and extending at an inward inclination is an outlet 66 for the chamber 59 and extending from the chamber 60 and at an inward inclination is an outlet 67 for such chamber. The outlets 66, 67 extend toward each other. The top of the housing 58 is provided with a tubular extension 68 which encloses the outlet 66, 67 and said extension 68 at its upper end is flanged as at 69. The outlet 66, 67 are also flanged at their upper ends, as at 70. Adjustably mounted on the flange 70 is a delivery member 71 provided with a pair of spouts 72, 73 which register respectively with the outlet 66, 67. The delivery member 71 is of curved contour so that when adjusted in one position it will deliver the snow to the right or when adjusted in another position it will deliver snow to the left. The delivery member 71 is flanged at its lower end as at 74. A sectional annulus 75 of channel-shape in vertical section overlaps the flanges 70 and 74 and seats on the flange 69. The sections of the annulus are detachably connected together at their ends, as at 75', see Figure 1. The holdfast devices between the sections of the annulus can be adjusted so that the delivery member can be shifted from the full line position as shown in Figure 4 to the dotted line position shown in such figure or to any other desired position. Bracing means, as indicated at 76, 77 and 78 are provided for the delivery member and an annulus 75. The flanges 69, 70 and 74 are of circular contour.

The fans provide snow removing or delivery means of the suction type and operate synchronously with the cutters 64, 65, but these latter attack the snow in advance of the action thereon by the fans, under such conditions the snow removing or delivery operation is greatly facilitated. To prevent the bottom of the housing 58 engaging with an uneven road surface, pieces of ice, or other obstacles, it is mounted on runners 79 having upturned front and rear ends.

Braking mechanisms for the rear wheels 27 are indicated at 27''. An operating means common to said mechanism is indicated at 27''' and is supported from the bars 9, 10.

When the machine is propelled, through the operation of the motor 23, the motors 20 and 21 are also set into operation, causing thereby a synchronous operation of the cutters and the suction devices or fans, and as the machine moves in a direct line against the snow, the cutters will cut the same and the snow will be taken up by the suction fans and delivered to the outlet 66, 67 from there into the delivery member 71 and the snow will be discharged to the right or left of the line of travel of the plow.

It is thought the many advantages of a motor driven snow plow, in accordance with

this invention, can be readily understood, and although the preferred embodiment of the invention is as illustrated and described, yet it is to be understood that changes in the details of construction can be had which will fall within the scope of the invention as claimed.

What we claim is:

A snow plow comprising a motor driven carriage, a vertical housing secured against the forward end of the carriage and having an open front, a pair of fan chambers within the housing and each having its forward wall open to provide an intake therefor, a fan within each of said chambers, a snow cutter

arranged forwardly of each fan chamber and at the open front of said housing, a vertical extension projecting from the upper walls of said fan chambers, a curved discharge pipe swivelled on the upper end of 20 said extension, and an inclined outlet pipe leading from each fan chamber, said outlet pipes converging and terminating at the upper end of said extension for delivering snow directly and independently from each fan 25 chamber to the discharge pipe.

In testimony whereof, we affix our signatures hereto.

CARL J. KJENSTAD.
JAMES M. GREEN.
